(57) **CLAIM**

The ornamental designs for an umbrella runner, as shown and described.

DESCRIPTION

FIG. 1 is a perspective view of a portion of one embodiment of my designs as illustrated in FIG. 2 showing an umbrella in phantom lining, an umbrella being one non-limiting environment in which the new designs can be used;

FIG. 2 is a top perspective view of one embodiment of an umbrella runner;

FIG. 3 is a bottom perspective view of the embodiment of FIG. 2;

FIG. 4 is a front view of the embodiment of FIG. 2;

FIG. 5 is a rear view of the embodiment of FIG. 2;

FIG. 6 is a right side view of the embodiment of FIG. 2;

FIG. 7 is a left side view of the embodiment of FIG. 2;

FIG. 8 is a top view of the embodiment of FIG. 2; and,

FIG. 9 is a bottom view of the embodiment of FIG. 2.

The broken lines represent environment and portions of the umbrella runner that form no part of the claimed design.
